UNITED STATES PATENT OFFICE.

DANTES R. REEFE, OF PLAINFIELD, NEW JERSEY.

LOCK.

SPECIFICATION forming part of Letters Patent No. 777,141, dated December 13, 1904.

Application filed December 24, 1903. Serial No. 186,431. (No model.)

To all whom it may concern:

Be it known that I, DANTES R. REEFE, a citizen of the United States, residing at Plainfield, in the county of Union and State of New Jersey, have invented a new and useful Improvement 5 in Locks, of which the following is a specification.

My invention is designed especially, though not exclusively limited, to use with albums intended to contain photographs or family records. Books of this type, known as "family albums," are usually of considerable thickness, varying according to the number of photographs that the album is intended to contain 15 and also varying according to the number of photographs actually inserted in them.

The object of my invention is a lock adapted to be placed on albums of this kind and which can be placed on various sizes of albums 20 as originally made and which after being permanently connected to any album can be adjusted to accommodate itself to the varying thickness of the album as photographs are added or taken from the album.

25 A further object of my invention is to provide a lock which is adapted for use as a clasp-lock adapted to be opened without a key and which can also be used as a lock openable only with a suitable key, so that the album may be 30 simply temporarily locked or may be permanently locked to those not possessing the key.

35 My invention consists in the novel features of construction and combination of parts hereinafter described, particularly pointed out in the claims, and shown in the accompanying drawings, in which—

Figure 1 is a perspective view of my lock applied to an album. Fig. 2 is a longitudinal section through the lock, the lock being in 40 position on the album. Fig. 3 is a perspective view of the connecting means between the two covers of the book detached and the lock removed. Fig. 4 is a plan view of the locking mechanism in detail, other parts being omitted, the bolt being shown in a disengaged position. Fig. 5 is a similar view, the 45 spring-pressed lock being removed and the key-operated lock being shown with the parts in the position occupied when the bolt is shot.

Fig. 6 is an elevation showing the key used 50 with the lock shown in Figs. 4 and 5.

In the drawings, A represents an album or other book, portfolio, or the like to which the lock is applied. A spring-plate B is bent upon itself on a pintle B', and the two leaves formed by bending the plate are sprung apart, and the free edge of the rear cover of the book is forced between them, and the leaves of the plate are secured by rivets or other desired means to the inner and outer faces of the said 60 cover, respectively. Along the bending-line the plate B is longitudinally and centrally cut out, exposing the pintle B', and to this portion of the pintle is hinged a plate, termed for convenience a "sleeve" B², having its side 65 edges bent inward to form guide-flanges, as is clearly shown in Fig. 3. A connecting-plate B³ is adapted to slide in the sleeve B², being guided by the flanges. The plate B³ has a rectangular cut-out or slotted portion 70 B', and the sleeve B² has formed on it, as by stamping, a shoulder B⁵, which projects into the slot formed in the connecting-plate B³ and limits the sliding movement of this plate with reference to the sleeve B². To the plate B³ 75 is hinged a rectangular piece of metal C, hinged to the plate approximately midway the slotted portion B' and the upper end of the plate, and the piece C when lifted upward into a vertical position extends above the plane of 80 the upper edge of the plate B³. To the end of the piece C opposite the end hinged to the plate B³ is hinged another metal plate C', and to distinguish it from the other parts it will be termed a "metal strip." This metal strip 85 C' is curved upwardly at its free end to form a guard C², and the strip or tongue carries on its under face a stud C³, notched to form a keeper for one of the locking-bolts.

The upper or front cover of the album is 90 cut away or reduced in thickness adjacent its free edge, and in the recess thus formed is secured the casing D of the lock proper. This casing has a cover D', having a larger area than the casing, and this cover is secured to 95 the non-recessed portion of the album-cover and conceals the cut-out portion and the lock-case. The cover D' is curved upward and then

downwardly adjacent its free front edge and extends downward over the front edge of the album or book cover and also over the upper edge of the connecting-plate B³, lying between 5 that plate and the metal piece C. This piece being in front of the cover D', it is obvious that the tongue or strip C' will rest upon the top of the cover D', the latter having a suitable aperture through which the keeper C² 10 projects into the lock-casing. The connecting-plate B³ extends upward into the forward portion of the case D through a slot D², and the plate B³ is apertured to receive the bolt of the ward D³, which is pivoted within the casing, the ward having the curvatured recess D⁴. The ward is longitudinally slotted, and a stud secured in the back of the casing projects through this slot, and on this stud is pivoted a tumbler D⁵. The tumbler is slotted at 15 D⁶, and a shoulder D⁷ projects into this slot, the shoulder being integral with the tumbler and substantially dividing the slot into two portions connected by a narrow passage-way. A lug D⁸, carried by the ward D³, projects 20 upwardly into the slot and is alternately engaged on opposite sides by the shoulder D⁷, the shoulder being held in engagement with said lug by a spring D⁸, bearing on the tumbler D⁵. A suitable stop D⁹ limits rear movement of the ward D³. A stud E, carried by 25 the back of the casing in alinement with the keyhole E', formed in the cover-plate D', forms a pivotal point for the key E² to rotate on. A locking-bolt F is slidably arranged in 30 the casing and is guided in its movements by a bifurcated portion which engages a stud or post F'. A slot F² is formed in the cover-plate adjacent the keyhole E', and through this slot extends the shank of a button F', the 35 shank at its lower inner end being connected to the bolt F, and by moving the button longitudinally on the cover-plate, the movement being limited by the length of the slot F², the bolt F is engaged and disengaged from the 40 keeper C³.

It will be obvious from the above description and from the drawings that the lock described is adapted for use with books of varying thickness, and the sliding movement 45 permitted in the plate B³ will always allow the bolt-receiving aperture of the plate to be in perfect alinement with the bolt of the ward.

The operation of the lock is as follows: When the tongue C' is folded down on the 50 cover-plate D', the keeper C² enters a suitable aperture in the cover-plate and is engaged by the bolt F, the latter being actuated by a suitable bow-spring G. The album is thus locked and can be readily unlocked by moving the button F³ to the rear end of the slot F², disengaging 55 the locking-bolt F from its keeper, and the tongue C' can be readily lifted by means of the curved guard C². When it is desired to double-lock the album, the parts being in the position

shown in Fig. 4, the key is inserted and turned 65 to the left, a socket in the end of the key fitting over the post or stud E. This movement brings the bit of the key into engagement with the recess of the ward D³ and also with a similar recess formed in the edge of the 70 tumbler. This moves the ward and tumbler on their pivotal points and moves the shoulder of the tumbler away from the lug on the ward D³. The ward then moves forward, the tumbler remaining stationary, and the lug is 75 passed through the narrow passage-way to the opposite side of the shoulder. As the bolt of the ward is shot forward into engagement with the bolt-receiving aperture of the connecting-plate B³ the bit of the key disengages 80 from the recesses of the ward and tumbler and the shoulder again engages the lug on the ward, this time on the opposite side. To unlock, a reverse operation takes place. It will be noted that the tongue C' covers the key-hole, and before the key is inserted the tongue is first unlocked by movement of the button F³, as above described, and the tongue thrown back.

Having thus fully described my invention, 90 what I claim as new, and desire to secure by Letters Patent, is—

1. A device of the kind described comprising a plate secured to one cover of a book, a lock secured upon the opposite cover, a plate 95 loosely connected to the first-mentioned plate and apertured to receive the bolt of the lock, a tongue adapted to rest on the lock-casing, means for locking the tongue to the lock-casing, and means pivotally connecting the tongue 100 and the apertured plate.

2. The combination with a plate secured to the free edge of a book-cover, of a plate hinged to the first-mentioned plate, a plate adapted to slide on the hinged plate and having a bolt-receiving aperture formed therein, a casing secured on the other book-cover in vertical alinement with the first-mentioned plate said casing having a keyhole therein, a key-operated bolt adapted to engage the bolt-receiving aperture of the connecting-plate, a metal piece hinged to the slidable plate intermediate the ends of said plate, a tongue hinged to the metal piece and adapted to lie over the lock-casing and keyhole, and means for locking the tongue 115 to the said casing.

3. A device of the kind described comprising a lock-casing secured to a book-cover, a ward in said casing having a bolt adapted to be projected from the casing said ward being slotted, a stud secured to the casing and extending into said slot, a tumbler pivoted on said stud, said tumbler being slotted and having a shoulder projecting into said slot, a spring bearing on the tumbler, a lug on the 120 ward extending into said slot of the tumbler adapted to be engaged on alternate sides by the shoulder, a plate having an aperture adapt-

ed to receive said bolt, means for connecting the apertured plate to the rear cover of a book, a metal piece hinged to the outer face of the apertured plate, a tongue connected to 5 the metal piece and adapted to rest on the lock-casing, a keeper carried by said tongue adapted to extend into the casing, and a spring-pressed bolt in the casing adapted to engage the said keeper, the said tongue being adapted 10 to prevent the insertion of a key into the casing to operate the ward and tumbler.

4. A device of the kind described comprising a plate adapted to be secured to one cover

of a book, a lock adapted to be secured to the opposite cover, a sleeve hinged to the plate, 15 a connecting-plate slidably secured in the sleeve and apertured to receive the lock-bolt, a tongue hinged to the connecting-plate and adapted to cover the lock-keyhole, and a spring-actuated bolt adapted to lock the said 20 tongue.

DANTES R. REEFE.
